UNITED STATES PATENT OFFICE.

ALEXANDER S. SPIEGEL, OF CHICAGO, ILLINOIS.

ROOFING-PACKAGE.

1,164,422.

Specification of Letters Patent. Patented Dec. 14, 1915.

Application filed February 23, 1915. Serial No. 10,091.

To all whom it may concern:

Be it known that I, ALEXANDER S. SPIEGEL, citizen of the United States, residing at Chicago, Illinois, have invented certain new and useful Improvements in Roofing-Packages, of which the following is a specification.

It has heretofore been proposed to make a roofing package by taking a strip or sheet 10 of double width; to divide this by a zigzag cut through the middle, and then wind the divided sheet into a roll with the serrated ends interlocking so as to protect the same.

It is the object of my invention to produce 15 the same sheet with serrated edges, and I utilize a sheet of double width and formed with a zigzag cut, but instead of rolling the sheet as cut and without separating the sections, I guide the serrated sections into overlapping relation to each other and pass them over a roller, whence they are rolled up 20 into a package. I have found by experience that the ends of the sections are more thoroughly protected and less likely to be broken off or bent out of shape than when they 25 are in engaging connection, and I also secure the further advantage of having a roll or package of only about half the width of the ordinary package.

30 In the drawing I show in Figure 1 a plan of the double width roofing section having the central zigzag cut, and at the right the guides for directing the severed ends into overlapping connection and with 35 the roller for receiving the doubled parts; Fig. 1^a is an edge view of Fig. 1; and Fig. 2 shows a view of the resultant package.

In carrying out my invention, I take a section of roofing material of double width and sever it centrally with a zigzag cut by 40 any suitable means, and then as shown in Fig. 1, the severed parts are separated by a roller *a* and then guided into overlapping connection by guides *b*, *b*, and from thence the layers pass to any suitable means for 45 rolling the doubled sections into a roll or package.

Fig. 2 shows the layers, one upon the other, with the zigzag edges protected by the adjacent solid portion of the roofing, 50 the zigzag edges being in reverse position.

What I claim is:—

1. A roofing package consisting of roofing material having zig zag edges, one section laid upon the other in reverse position 55 so as to protect the zig zag edges, substantially as described.

2. The method herein described, consisting in taking a roofing section of double width, cutting the same centrally into two 60 sections, each having one irregular edge, guiding the cut ends into overlapping relation and then forming the overlapped sections into a package, with the irregular edges of the sections superposed in reverse 65 position, substantially as described.

In testimony whereof, I affix my signature in presence of two witnesses.

ALEXANDER S. SPIEGEL.
